FABRIC OR SIMILAR ARTICLE

Janet Heller, Van Nuys, Calif.

Application December 5, 1949, Serial No. 6,415

Term of patent 14 years

(Cl. D92—1)

To all whom it may concern:

Be it known that I, Janet Heller, a citizen of the United States, residing at Van Nuys, county of Los Angeles, State of California, have invented a new, original, and ornamental Design for a Fabric or Similar Article, of which the following is a specification, reference being had to the accompanying drawing, forming a part thereof.

The figure is a plan view of a fabric or similar article, showing my new design.

A design unit is contained between the broken lines and is repeated as indicated.

I claim:

The ornamental design for a fabric or similar article, as shown and described.

JANET HELLER.
